DESIGN FOR A SHOE

Saveria Burrafato, Brooklyn, N. Y.

Application February 9, 1944, Serial No. 112,517

Term of patent 7 years

(Cl. D7—7)

To all whom it may concern:

Be it known that I, Saveria Burrafato, a citizen of the United States and resident of the Borough of Brooklyn, county of Kings, city and State of New York, have invented a new, original, and ornamental Design for a Shoe, of which the following is a specification, reference being had to the accompanying drawing, forming a part thereof.

Fig. 1 is a front perspective view of a shoe showing my new design; and

Fig. 2 is a side perspective view of the opposite side shown in Fig. 1.

I claim:

The ornamental design for a shoe, substantially as shown.

SAVERIA BURRAFATO.
